(57) **CLAIM**

The ornamental design for a vaporization device, as shown and described.

DESCRIPTION

FIG. 1 is a perspective view showing the bottom end of a vaporization device showing of my new design;

FIG. 2 is a perspective view showing the top end of my new design;

FIG. 3 is a bottom elevational view of my new design;

FIG. 4 is a bottom elevational view of my new design;

FIG. 5 is a left side elevational view of my new design, the appearance of any portion of the article between the break lines forms no part of the claimed design;

FIG. 6 is a right side elevational view of my new design, the appearance of any portion of the article between the break lines forms no part of the claimed design;

FIG. 7 is a front plan view of my new design, the appearance of any portion of the article between the break lines forms no part of the claimed design; and,

FIG. 8 is a back plan view of my new design, the appearance of any portion of the article between the break lines forms no part of the claimed design.

A broken line showing is for illustrative purposes only and forms no part of the claimed design.

A break line indicates indeterminate length.
